UNITED STATES PATENT OFFICE.

JOHN F. O'CONNOR, OF CHICAGO, ILLINOIS, ASSIGNOR TO WILLIAM H. MINER, OF CHICAGO, ILLINOIS.

FRICITION DRAFT-GEAR FOR RAILWAY-CARS.

1,156,092.

Specification of Letters Patent.

Patented Oct. 12, 1915.

Application filed October 22, 1912. Serial No. 727,164.

To all whom it may concern:

Be it known that I, JOHN F. O'CONNOR, a citizen of the United States, residing in Chicago, in the county of Cook and State 5 of Illinois, have invented a certain new and useful Improvement in Friction Draft-Gears for Railway-Cars, of which the following is a full, clear, concise, and exact description, reference being had to the accompanying drawing, forming a part of this 10 specification.

My invention relates to improvements in friction draft gears for railway cars.

The object of my invention is to provide 15 a compact friction draft gear of high shock absorbing capacity.

In the drawings Figure 1 is a side elevation partly in longitudinal section on line 1—1 of Fig. 3 of a railway draft rigging 20 embodying my invention. Fig. 2 is a one-half cross section on line 2—2 of Fig. 1. Fig. 3 is a plan view partly in horizontal section on line 3—3 of Fig. 1. Fig. 4 is an enlarged detail view of the draft gear in cross section on line 4—4 of Fig. 5. Figs. 5 and 6 are each side elevations of the draft gear partly in vertical longitudinal section along line 5—5 of Fig. 4; Fig. 5 showing the gear with its parts in normal position, and Fig. 6 showing the parts compressed. Fig. 7 is a perspective view of one of the anti-friction rollers. Fig. 8 is a perspective view of the wedge. Fig. 9 a perspective view of one of the friction shoes. Fig. 10 a perspective view of a supplemental follower. Fig. 11 a perspective view of one of the movable spring seats, and Fig. 12 a perspective view of one of the supplemental friction shoes.

40 Referring to the drawings 13, 13 represent draft sills or parts of the car frame to which the draft rigging is attached, 14, 14 stop members secured thereto and provided with front and rear stop shoulders 15, 15 and 45 16, 16 respectively. The stop members are each provided with the longitudinal groove 17 to receive the limbs 18, 18 of the longitudinally disposed draft yoke 19, which reciprocate therein. The draft yoke is suitably secured to the draw-bar 20 by the draw-bar key 21. The end sill 22, buffer block 23, striking plate 24 and draw-bar carry iron 25 are all of usual construction.

50 The draft gear or compression resisting member 26 is mounted within the draft yoke

and is secured against downward displacement by the tie plate 27, which is suitably secured at either end to the draft members and stop members. The compression resisting member 26 comprises with the parts 60 hereinafter described a housing or shell 28, which is provided with a central longitudinal friction chamber 29, and adjacent thereto and parallel therewith an upper spring chamber 30 and a lower spring chamber 31. 65 The shell or housing 28 is of a general rectangular shape open at its forward end and closed at its rear end by the preferably integral plate 32.

In normal position or in buffering movement of the gear the rear outer faces of the shell engage the rear stop shoulders 16, 16. The friction chamber 29 of the shell or housing is in general shape a hollow cylinder provided with the internal friction face 33 70 with which the friction shoes 34 engage. The friction shoes are preferably three in number, each provided with the outer friction face 35 and the inner wedge face 36, which is acted upon through the anti-friction roller 37 by the wedge 38. The wedge 38 preferably has three wedge faces 39, or one for each of the friction shoes, with an anti-friction roller 37 engaging between each wedge face and the adjacent friction shoe. 75 The friction shoes are annularly arranged, and each is provided with an inner shoulder 40 to form a seat for the supplemental follower 41. The supplemental follower 41, the wedge 38 and the rear plate 32 of the 80 housing are suitably apertured longitudinally for the passage of the central connecting rod 42, the head 43 of which is received within the recess 44 in the forward face of the wedge, and the nut 45 of which is 85 received in the recess 46 in the rear outer face of the shell.

The friction chamber 29 is provided at its rear end with upper and lower similar openings 48 leading to the upper and lower 130 spring chambers 30 31. The said openings each permit the passage of a supplemental friction shoe 49. The said supplemental shoes are preferably two in number, and are each in preferred form of a general 135 semi-lunar shape in longitudinal section. Each is provided with a friction face 50 conforming to the friction face 51 provided for each in the rear inner face of the shell or housing. The friction faces 51 each ex- 140

tend substantially from the center of the rear end of the friction chamber 29 to the center of the rear end of one of the spring chambers. The spring chambers each contain a coil spring or springs 58, preferably two, arranged side by side, which are seated in each chamber at their rear ends against a movable spring seat 52. Each supplemental shoe 49 is provided at its inner end, that is the end within the friction chamber, with a transverse rounded shoulder 53 which engages the rear face 54 of the supplemental follower 41. At its outer end, that is the end within the spring chamber, each supplemental friction shoe is provided with rounded transverse shoulders 55 corresponding in number with the springs in each spring chamber.

The movable spring seat 52 is rearwardly provided with suitable recesses 56, one to receive each shoulder 55 of the supplemental friction shoe engaging therewith, and preferably said movable spring seat is provided on its forward face with bosses 57 around which the adjacent spring 58 is seated. The springs 58 are suitably seated at their forward ends. I prefer to seat them against the rear face 59 of the front follower 60, which also engages the front face 61 of the wedge 38 and is vertically arranged within the draft yoke.

The shell is outwardly laterally provided with the upright webs 62 perforated longitudinally of the shell to receive the outer connecting rods 63, 63, which are preferably four in number, two on either side of the shell. Said connecting rods pass through the front follower, and the nut 64 of each is received within a suitable recess 65 in the forward face of the follower. The head 66 of each rod is received within a recess 67 in the rear face of the shell.

It will be apparent that upon movement of the draw bar stresses transmitted to the gear will be absorbed not only by the friction shoes 34 but also by the supplemental shoes 49, and through these shoes by the springs 58. It will also be clear that the springs 58 will also be acted upon at their forward ends through their engagement with the front follower. The transverse rounded shoulders at the ends of the supplemental shoes permit the necessary oscillation of the same when the gear is in action.

In normal position of the parts within the shell, as illustrated in Fig. 5 of the drawings, the springs 58 are forwardly extended beyond the openings of the spring chambers. Under full compression the parts will assume the positions within the shell illustrated in Fig. 6.

I claim:

1. A draft gear for railway cars comprising a shell provided with a central friction chamber and parallel adjacent spring cham-

bers, friction compression resisting members with the friction chamber and springs within the spring chambers, and friction means for operatively connecting the friction compression resisting members with said springs.

2. A draft gear for railway cars comprising a shell provided with a central friction chamber and parallel adjacent spring chambers, friction compression resisting members within the friction chamber and springs within the spring chambers, and means for operatively connecting the friction compression resisting members with said springs, said means comprising curved shoes engaging the friction compression resisting members at one end and the springs at the other end.

3. In a railway draft rigging, a cushioning member comprising a shell having a central friction chamber and parallel adjacent spring chambers, a wedge and friction shoes within said friction chamber, and springs within the spring chambers, openings within said shell between the friction chambers and spring chambers, and shoes passing through said openings engaging the friction compression resisting members at one end and the springs at the other end.

4. In a draft rigging for railway cars, a cushioning member comprising a shell, a friction chamber and adjacent spring chambers in said shell, said spring chambers being arranged on opposite sides of said friction chambers, the said chambers being closed at their rear end, openings provided between each spring chamber and the friction chamber, friction compression resisting members within the friction chamber, springs within the spring chamber, the rear inner face of the shell being provided along the said openings with a friction face, friction shoes having friction faces each engaging one of said friction faces of the shell, and in engagement with the friction compression resisting members at one end and the springs at the other end.

5. In a draft rigging for railway cars, a cushioning member comprising a shell having a friction chamber and spring chambers adjacent and parallel thereto, friction compression resisting members within the friction chambers, and springs within the spring chambers, a shoe for each spring chamber engaging the springs therein at one end and engaging the friction members within the friction chamber at the other end.

6. In a railway draft rigging, a cushioning member comprising a shell having a central friction chamber, and at the sides thereof spring chambers having openings leading to the friction chamber, friction elements within the friction chambers and springs within the spring chambers, and

- shoes connecting the springs with the friction elements, the said shoes having frictional bearing against the shell.
7. In a railway draft rigging, the combination of draft sills, stop members, draw bar and draft yoke, of a cushioning member and a front follower, the said cushioning member comprising a shell having a central friction chamber and friction elements within said chamber, and spring chambers beside and parallel to the friction chamber, shoes connecting the said friction elements with the said springs, the said springs being seated at their forward ends against the front follower.
8. In a railway draft rigging, the combination of draft sills, stop members, draw bar and draft yoke, of a cushioning member and a front follower, the said cushioning member comprising a shell having a central friction chamber and friction elements within said chamber, and spring chambers beside and parallel to the friction chamber, shoes connecting the said friction elements with the said springs, the said springs being seated at their forward ends against the front follower, and connecting rods connecting the said shell with the front follower.
9. In a railway draft rigging, the combination with the draw bar, draft yoke, draft sills, stop members, of a shell and front follower, the said shell having a friction chamber and spring chambers beside the said friction chamber, friction elements within the friction chamber and springs within the spring chamber, the said springs being seated at their forward ends against the front follower, and means connecting the springs with the friction elements adapted to compress the said springs against the front follower.
10. In a railway draft rigging, a cushioning member comprising a shell, a friction chamber and spring chambers alongside the friction chamber in said shell, friction shoes and a wedge within the friction chamber, and springs within the spring chambers seated at their forward ends against the front follower, and means connecting the friction shoes with the rear ends of said spring, and adapted to compress said springs upon movement of the friction shoes.
11. In a railway draft rigging, the combination with the draw bar, draft sills, stop members and draft yoke, of a follower and a cushioning member, the cushioning member comprising a shell having a central friction chamber and spring chambers beside the friction chamber, friction shoes and wedge within the friction chamber, and springs within the spring chamber, supplemental friction shoes adapted to co-act be-
- tween the friction members and the springs 65 and in frictional engagement with the shell.
12. In a railway draft rigging, a cushioning member comprising a shell having a central friction chamber and a pair of spring chambers, one on either side of the said friction chambers, friction shoes and wedge within the friction chamber, and a pair of springs in twin arrangement in each of the spring chambers, a movable spring seat for each set of springs, and a supplemental friction shoe 70 for each spring chamber adapted to engage the said spring seat at its one end and to operatively engage the members within the friction chamber at its other end.
13. In a railway draft rigging, a cushioning member comprising a shell having a friction chamber and spring chambers arranged along the side thereof, friction elements within the friction chambers and springs in each of the spring chambers, and supplemental friction shoes in frictional engagement with the shell adapted to engage a spring at one end and the friction members at the other end.
14. In a railway draft rigging, a cushioning member comprising a shell having a friction chamber and adjacent spring chambers, an opening from each spring chamber to the friction chamber, a supplemental friction shoe extended through each of said 90 openings, each of said supplemental friction shoes operatively connecting the friction elements in the friction chamber with the springs in one of the spring chambers.
15. In a railway draft rigging, a cushioning member comprising a shell having a central friction chamber and parallel adjacent spring chambers, a wedge and friction shoes within the spring chamber, and a supplemental follower in engagement with said 100 friction shoes, an opening between each spring chamber and the friction chamber, a supplemental friction shoe passed through each of said openings and in frictional engagement with the rear inner portion of the shell, each of said supplemental friction shoes being in engagement with said supplemental follower at one end and with said springs at the other end.
16. In a railway draft rigging, a cushioning member comprising a shell having a central friction chamber and parallel adjacent spring chambers, a wedge and friction shoes within the spring chamber, and a supplemental follower in engagement with said 110 friction shoes, an opening between each spring chamber and the friction chamber, a supplemental friction shoe passed through each of said openings and in frictional engagement with the rear inner portion of the shell, each of said supplemental friction shoes being in engagement with said supplemental follower at one end and with said

springs at the other end, the said supplemental shoes being each of a semi-lunar shape.

17. In a draft gear, in combination, a friction chamber, spring chambers at the sides thereof, and substantially longitudinally coextensive therewith, friction compression resisting members within the friction chamber, and springs within the spring chambers, and friction means operatively connecting the friction compression resisting members and the springs.

18. In a draft gear, in combination a friction chamber, friction compression resisting members therein, spring at the sides of the friction chamber, and substantially longitudinally coextensive with the friction mechanism, and friction means operatively connecting the friction compression resisting members with the springs.

19. In a draft gear, a friction chamber, spring chambers adjacent thereto and substantially longitudinally coextensive therewith, friction compression resisting members within the friction chambers, and springs within the spring chambers and shoes connecting the friction compression resisting members with the springs.

20. In a draft gear, a friction chamber, springs at the sides of said chamber, friction compression resisting members within the friction chamber, and friction means operatively connecting the friction compression resisting members to said springs, the said springs being disposed longitudinally of the friction chamber.

21. In a shock absorbing mechanism, the combination with a follower, of a friction chamber, friction compression resisting members within said chamber, springs located exteriorly of said chamber, means operatively connecting the friction compression resisting mechanism with one end of each of said springs, and means, movable longitudinally of the gear for pressing the other ends of said springs upon movement of the follower.

22. In a shock absorbing mechanism, the combination with a follower, of a friction chamber, longitudinally movable friction shoes within said chamber, a wedge coöperating with said shoes and in engagement with the follower, springs located outside of said chamber, means operatively connecting the friction shoes with one end of each of said springs, and means, movable longitudinally of the gear for pressing the opposite ends of said springs upon movement of the follower.

23. In a shock absorbing mechanism, the combination with a friction chamber, friction compression resisting members within

said chamber, a spring located alongside the friction chamber on the exterior thereof and substantially longitudinally coextensive 65 with the friction mechanism, and friction means operatively connecting the friction compression resisting members with one end of said spring.

24. In a shock absorbing mechanism, the 70 combination with a friction chamber, friction compression resisting members within said chamber, a spring located alongside the friction chamber on the exterior thereof and substantially longitudinally coextensive 75 with the friction mechanism, means operatively connecting the friction compression resisting members with one end of said spring and means for pressing the opposite 80 end of said spring simultaneously with the operation of the friction mechanism.

25. In a shock absorber, the combination with stop members, of a friction shell, a follower, friction elements within said shell, said elements including longitudinally movable friction shoes and a wedge coöperating therewith, springs located exteriorly of the shell, said springs being seated at their ends against the follower, and means connecting the springs with the friction shoes adapted 90 to compress the said springs against said follower.

26. In a shock absorber, the combination with a plurality of springs and a friction device arranged side by side, and means for 95 simultaneously operating the friction device and compressing the springs from both ends thereof.

27. In a shock absorbing mechanism, the combination with a follower, of a friction 100 shell, friction shoes and a wedge mounted within said shell, the wedge being in engagement with the follower, springs in engagement with said follower, and means operatively connecting the friction shoes 105 with the ends of said springs opposite to those ends which are in engagement with the follower.

28. In a shock absorbing mechanism, the combination with a friction shell having a 110 plurality of friction shoes and a wedge mounted therein, of a follower, said follower being adapted to operate said wedge and thereby the friction shoes, springs arranged parallelly with the friction shell and out of alignment with the axis thereof, and means operatively connecting the friction shoes with said springs, said means including supplemental friction elements.

JOHN F. O'CONNOR.
